UNITED STATES PATENT OFFICE.

BENJAMIN C. SKINNER, OF OAKLAND, CALIFORNIA.

GAS-ENGINE VALVE.

No. 857,762.

Specification of Letters Patent.

Patented June 25, 1907.

Application filed January 19, 1905. Serial No. 241,817.

To all whom it may concern:

Be it known that I, BENJAMIN C. SKINNER, a citizen of the United States, residing at Oakland, in the county of Alameda and State of California, have invented certain new and useful Improvements in Gas-Engine Valves, of which the following is a specification.

My invention relates to gas engines, and more particularly to a single slide valve for controlling the inlet and exhaust and for closing the compression space.

I have embodied my invention in an engine of the four-cycle type, and such an engine is shown in the accompanying drawings:

Figure 1 is a side elevation with one end of the cylinder in section: Fig. 2 is a plan view: Fig. 3 is an end elevation of the cylinder head: Fig. 4 is in the nature of a diagram showing the inlet open and indicating the position of the connections for operating the valve, at that time: Fig. 5 is a similar kind of view, but shows the exhaust open: Fig. 6 is a like view, showing both inlet and exhaust closed as they would be at the time of compression.

I show a horizontal engine in the drawings, but my invention can be applied to the vertical type of engine as well. The bed frame 1, supports the cylinder 2 having the usual piston which is operated by the engine shaft 3 and crank 4, through the connecting rod 5. On the engine shaft is a gear 6, which meshes with another gear 7, journaled in the engine bed and which is of larger size so as to revolve, relatively to gear 6, in the ratio of 1 to 2. Revolving with gear 7 is a cam 8 of the peculiar shape shown. This cam has a high side 9, concentric portion 11, and depression 12. The cam operates the valve controlling lever 13, which is secured to a rock shaft 14 journaled in the bed frame. On this rock shaft is a rod 15 which extends longitudinally in the bed frame, and is connected by a link 16 to the slide valve 17, which is substantially spool shaped so that it has two heads which fit the passage 18 in the cylinder head and an intermediate stem. The cylinder head is provided with the said transverse passage for the valve, and with a single, and preferably central port 19 which connects this passage with the interior of the cylinder. Beyond the passage 18 the cylinder head is provided with an inlet port 21, and an exhaust port 22. Both the cylinder

and cylinder head may be and preferably are water jacketed as shown. Secured to the end of the cylinder head is a tubular structure having a central open passage 23 communicating with the exhaust port, and a surrounding space 24, communicating with the inlet port. A pipe 25 supplies the operating charge and is connected into the space 24.

The relation between the central port 19, the valve and the inlet and exhaust ports 21 and 22 will be evident by a comparison of Figs. 4, 5, and 6. The high side of the cam operates the valve lever so as to open the inlet as shown in Fig. 4. The depression in the cam permits the end of the valve lever to fall in whereby the exhaust is opened as shown in Fig. 5. The concentric part of the cam renders the valve lever inoperative, the valve being in the intermediate position shown in Fig. 6, in which it is closing both the inlet and exhaust. This is the position during the compression stroke and the following working stroke.

Ignition of the charge may be made by any suitable igniter but I have not shown such an igniter as it forms no part of my invention, and is not required for a full comprehension of the same.

The operation of the engine will be very easily understood. The charge is drawn in through the inlet passage and port, which charge, owing to the spool shape of the valve can enter the cylinder through the single port 19, the parts being then in the position of Fig. 4. The transition of the free end of the valve rod from the high side of the cam to its concentric portion closes both inlet and exhaust and the space surrounding the narrow part of the spool-shaped valve becomes a part of the compression space. During the compression and the succeeding stroke caused by the explosion, the valve remains in this intermediate position as indicated by Fig. 6. On the exhaust stroke, the free end of the valve lever falls into the depression in the cam as shown in Fig. 5, and the burned out charge escapes through the port 19, around the stem of the spool, and out by way of the open exhaust passage. The free end of the valve lever is preferably provided with a roller 26.

The advantages of my single slide valve will readily be apparent. It greatly simplifies the construction of gas engines both as to the construction of the valves and to the

connections for operating them. The valve motion is exceedingly simple, positive and effective.

It should be stated that it is not necessary to locate the valve so that it shall slide vertically in the cylinder head although I prefer such location. It can be arranged at the top, side or bottom of the cylinder, in the proper proximity to a single port, and with an arrangement of inlet and exhaust passages substantially such as are shown in the drawing and herein described.

I do not limit myself to the exact constructions herein described and shown in the drawings, as I desire to avail myself of such modifications and equivalents as fall properly within the spirit of my invention.

Having thus fully described my invention, what I claim as new and desire to secure by Letters Patent, is:—

In a gas engine, a cylinder having a piston

chamber and a head, said head having a passage extending diametrically therethrough, said piston chamber having a single central port communicating with said passage, said head having inlet and outlet ports therein communicating with the passage, a small cylinder 20 arranged at right angles on the end of the cylinder head, said small cylinder having an exhaust space connected with the 25 exhaust port and an inlet space surrounding the exhaust space and connected with the inlet port and a slide valve in said passage controlling the inlet and exhaust ports.

In testimony whereof I have affixed my 30 signature, in presence of two witnesses, this 15th day of November, 1904.

BENJAMIN C. SKINNER.
